UNITED STATES PATENT OFFICE.

BENJAMIN FRY LUTZ, OF LITITZ, PENNSYLVANIA.

DAMPER-REGULATOR.

No. 871,716.

Specification of Letters Patent.

Patented Nov. 19, 1907.

Application filed December 14, 1905. Serial No. 291,773.

To all whom it may concern:

Be it known that I, BENJAMIN FRY LUTZ, a citizen of the United States, residing at Lititz, in the county of Lancaster and State 5 of Pennsylvania, have invented certain new and useful Improvements in Damper-Regulators, and I do declare the following to be a full, clear, and exact description of the invention, such as will enable others skilled in 10 the art to which it appertains to make and use the same.

This invention relates to improvements in automatic damper regulators.

The object of the invention is to provide a 15 device of this character by means of which the dampers of a furnace or heater may be regulated automatically and at any desired time.

With the above and other objects in view, 20 the invention consists of certain novel features of construction, combination and arrangement of parts, as will be hereinafter described and claimed.

In the accompanying drawing is shown a 25 diagrammatic view of the invention.

Referring more particularly to the drawings, 1 denotes a furnace which may be of any suitable design and construction, but is here shown as having a check door 2 and 30 a draft door 3. Connected to the draft door 3 and the check door 2 are chains 4 and 5, said chains being united at a suitable point and passed through guide pulleys 6. Connected to the chain 4 is an operating 35 weight 7, to which is secured a hook 8.

When the weight 7 is in an operative position with the furnace draft door 3 closed and the check door 2 open, the hook 8 on said weight is engaged with a pivotally mounted 40 supporting lever 9. Said lever is held in position by means of a pivotally mounted detent 10 provided with a laterally extending curved trip arm 12 which projects into the path of movement of a trip lever 13 45 secured to the alarm winding shaft of a clock 14, whereby when the alarm mechanism is released, said lever will engage the trip arm 12 and will disengage the detent 10 from the lever 9. The lever 9 being thus released 50 will permit the weight 7 to drop which action will draw upon the chains 4 and 5, thereby closing the check door 2 and opening the draft door 3. If desired the operating mechanism and the clock 14 may be ar-

ranged in a suitable box or casing 15, which 55 is secured upon the wall or other suitable support.

In operation, the alarm clock is wound and set to operate at any desired hour, thereby releasing the weight holding mechanism 60 and permitting the weight to drop and operate the furnace draft, as hereinbefore described.

From the foregoing description, taken in connection with the accompanying drawings, the construction and operation of the invention will be readily understood without requiring a more extended explanation.

Various changes in the form, proportion and the minor details of construction may be 65 resorted to without departing from the principle or sacrificing any of the advantages of this invention, as defined by the appended claims.

Having thus described my invention, what 75 I claim as new and desire to secure by Letters-Patent, is:—

In combination with a furnace and its draft and fuel or check doors, a draft regulator embracing guide rolls, and a flexible 80 connection having one end attached to the draft door, said flexible connection also having a like branch connection with the fuel or check door intermediate of said guide rolls, a counter-balance weight connected to one 85 end of said connection and provided with an engaging hook, a horizontal supporting lever, engaged at its forward end with said hook for sustaining said weight, a pivoted detent 90 hung at its upper end and having a shoulder at its lower end engaged with the rear end of said lever for the retention of said lever in weight-supporting position, said detent being adapted to swing by gravity to engaging position and having at its lower end an 95 upwardly curved trip-arm serving as a weight for the retention of said lever in effective position, and actuating mechanism having a tripping lever adapted to engage said trip-arm for swinging said detent to released 100 position.

In testimony whereof I have hereunto set my hand in presence of two subscribing witnesses.

BENJAMIN FRY LUTZ.
